US00D929439S

(12) **United States Design Patent** (10) **Patent No.:** **US D929,439 S**
(45) **Date of Patent:** **** Aug. 31, 2021**

(54) **DISPLAY SCREEN OR PORTION THEREOF WITH GRAPHICAL USER INTERFACE**

(71) Applicant: **State Farm Mutual Automobile Insurance Company**, Bloomington, IL (US)

(72) Inventors: **Neil Stoeckle**, San Francisco, CA (US); **Le Yang**, San Mateo, CA (US)

(73) Assignee: **State Farm Mutual Automobile Insurance Company**, Bloomington, IL (US)

(**) Term: **15 Years**

(21) Appl. No.: **29/724,645**

(22) Filed: **Feb. 18, 2020**

Related U.S. Application Data

(63) Continuation of application No. 29/630,561, filed on Dec. 21, 2017, now Pat. No. Des. 876,457.

(51) **LOC (13) Cl.** **14-04**

(52) **U.S. Cl.**

USPC **D14/487**; D14/492

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof and form no part of the claimed design.

1 Claim, 1 Drawing Sheet
